US00D896827S

(12) **United States Design Patent** (10) **Patent No.:** **US D896,827 S**
Boutousov et al. (45) **Date of Patent:** **** Sep. 22, 2020**

(54) **DISPLAY SCREEN INCLUDING A DENTAL LASER GRAPHICAL USER INTERFACE**

(71) Applicant: **BIOLASE, INC.**, Irvine, CA (US)

(72) Inventors: **Dmitri Boutousov**, Dana Point, CA (US); **Richard Jackson**, Trabuco Canyon, CA (US); **Douglas Patton**, Costa Mesa, CA (US)

(73) Assignee: **BIOLASE, INC.**, Irvine, CA (US)

(**) Term: **15 Years**

(21) Appl. No.: **29/658,791**

(22) Filed: **Aug. 2, 2018**
